(57) CLAIM

The ornamental design for a stool with a hanging banner, as shown and described.

DESCRIPTION

FIG. 1 is a front and rear view of a stool with a hanging banner incorporating my new design;

FIG. 2 is a front and rear view of a second embodiment;

FIG. 3 is a front and rear view of a third embodiment;

FIG. 4 is a front and rear view of a fourth embodiment;

FIG. 5 is a front and rear view of a fifth embodiment;

FIG. 6 is a front and rear view of a sixth embodiment;

FIG. 7 is a front and rear view of a seventh embodiment and an alternative left and right side view;

FIG. 8 is a front and rear view of a eighth embodiment; and an alternative left and right side view;

FIG. 9 is a front and rear view of a ninth embodiment; and an alternative left and right side view;

FIG. 10 is a front and rear view of a tenth embodiment; and an alternative left and right side view;

FIG. 11 is a left and right side view of the first through tenth embodiments; and,

FIG. 12 is a bottom view of the first through tenth embodiments.

The broken line showing is for illustrative purposes only and forms no part of the claimed design.
